SIGNAL AND CONTROL SYSTEM FOR
ELEVATORS

Phillip C. Keiper, Chicago, and Frank E. Lewis, deceased, late of Chicago, Ill., by Edgar M. Beuton, administrator, Park Ridge, Ill., assignors to Westinghouse Electric Elevator Company, Chicago, Ill., a corporation of Illinois

Application November 3, 1934, Serial No. 751,358

28 Claims. (Cl. 177—336)

Our invention relates to signal and control systems for elevators.

In some elevator systems, it is desirable to operate the cars from terminal to terminal upon a predetermined schedule. In other systems, it is desirable to operate the cars only when calls are to be answered. When cars are operated in the latter system, there are some periods in which the majority of the calls may be in the down direction, and some periods in which the majority of calls may be in the up direction. In these latter operations, it is desirable to have the signal and control systems so operate that the cars, if operating from a lower terminal, will, while being operated upwardly, stop at the highest registered call, regardless of whether it is an up direction or a down direction call, and if operating from an upper terminal, will stop at the lowest registered stop call, regardless of whether it is an up or a down direction call.

Therefore, one object of our invention is to provide a control and signal system by which the cars will be automatically stopped or will receive a stop signal when they reach the highest registered call regardless of the direction of the registered call or, on the other hand, will stop or receive a stop signal when they reach the lowest registered call regardless of its direction.

It is also an object of our invention to provide a flexible elevator system under which the cars may be operated in the most efficient manner under either a predetermined schedule or without any schedule of operation and under either a button control system or a pre-registered signal system.

Other objects of our invention will, in part, be obvious and will, in part, appear hereinafter.

For a clearer understanding of our invention reference may be had to the accompanying drawings, in which:

Figure 1 is a diagrammatic representation of an elevator system embodying a group of two cars to be operated in accordance with our invention;

Fig. 2 represents the arrangement of the contact segments and contact brushes on the floor selector for one of the cars shown in Fig. 1;

Figs. 3 and 4 collectively constitute a diagrammatic representation, in what is known as a straight line style, of the signal and control system employed in operating a group of two cars shown in Fig. 1; and

Figs. 3A and 4A collectively constitute an ex-

planatory illustration of the relays embodied in Figs. 3 and 4.

In the illustration of the relays in Figs. 3A and 4A, their coils and contact members are disposed in horizontal alignment with their positions in the straight line circuits of Figs. 3 and 4, so that the reader may readily determine the identification of any relay, the number and kind of its contact members and the position of its coil and its contact members in the "straight line" circuits.

For convenience in reading the drawings, Fig. 4 should be placed under Fig. 3, Fig. 3A should be placed beside Fig. 3, and Fig. 4A should be placed under Fig. 3A and beside Fig. 4.

Also for convenience, the main relays included in the system are designated as follows:

C=Car buttons.	
CC=Car button holding coils.	20
D=Down direction switch.	
E=Decelerating inductor relay.	5
F=Stopping inductor relay.	
G=Inductor maintaining relay.	
H=Inductor restoring relay.	10
J=Floor buttons.	
K=Opposite call device or relay.	15
N=Call below system relay.	
P=Call above system relay.	
Q=Restoring coils on registering relays.	25
R=Floor button registering relays.	30
S=Stopping relay responsive to car buttons.	
T=Stopping relay responsive to floor buttons.	
U=Up direction switch.	
V=High speed relay.	35
W=Up preference relay.	
X=Down preference relay.	
Y=Preventing relay (prevents car from answering an opposite direction call while inside call exists).	40

Although the control and signal system is illustrated as provided for two cars, A and B for serving five floors, it is to be understood that our invention may be utilized in connection with any number of cars serving any number of floors.

The relays for car B are given the same designation as those for car A with the letter "B" pre-fixed thereto. The letters U and D indicate up and down direction. The prefix numerals indicate the floors, and the suffix numerals indicate the contact members of the relays. For instance, the reference letters BV indicate the high speed relay for car B, while BV3 indicates the pair of contact members of that relay disposed in the circuit leading to brushes B32 and B42.

- The contact members 5DR indicate the down call registering relay at the fifth floor, while 5DR2 indicates the contact members of that relay disposed in its self-holding circuit.
- 5 Referring more particularly to the drawings the car A is suitably suspended by a cable 11, which passes over a hoisting drum 13 to a suitable counterweight 15. Referring to the control system for car A as shown in Figs. 3 and 4, the hoisting drum 13 is directly coupled to an armature 17 of a suitable hoisting motor 18, the field winding 19 of which is connected for constant voltage energization to a source of supply designated by the supply conductors L+1 and L-1.
- 10 15 A variable voltage system of control such as the Ward Leonard system may be provided for operating the hoisting motor 18, wherein the armature 17 is connected in a closed circuit with the armature 21 of the generator 22. The generator is provided with a separately excited field winding 23 and a cumulative series field winding 24. A resistor r1 is connected in the circuit of the separately excited field winding for controlling the speed of the generator.
- 15 20 25 The armature 21 of the generator is operated by a suitable driving motor 25 connected to any suitable source of energy (not shown). A brake 5 operated by an electromagnet 6 is provided for applying a braking effect to the hoisting drum 13 when the car is brought to a stop, the brake magnet 6 being energized to release the brake 5 when the car is running, and being deenergized to apply the brake when the supply of power to the car is cut off.
- 30 35 40 The direction and speed of the hoisting motor 18 may be suitably controlled by controlling the direction and the value of the excitation current supplied to the separately excited field winding 23.
- 45 50 55 The direction of excitation current for the field winding may be suitably controlled by an up direction switch U and a down direction switch D. The value of the current supplied to the field winding may be controlled by means of a high speed relay V for connecting and disconnecting the resistor r1. The closing of the contact members V1 and the opening of the contact members V2 and V3 is retarded by a dashpot 85 to get smoother starting and to provide time for effecting cancellation of a call upon reversal of the car.
- 55 60 65 The up direction and the down direction switches are controlled by a car switch CS disposed in the car. When the car switch is moved in a clockwise direction, the down direction switch D is energized to start the car downwardly. When the car switch is moved in a counterclockwise direction, the up direction switch U is energized to start the car upwardly.
- 70 75 80 The car may be started by operating a car switch and may be stopped either by a push button control system or by response to a preregistered signal system. If the push button control system is used, the car is started by moving the car switch to start the car and is stopped by the attendant pressing a push button in the car or by waiting passengers at the floors pressing push buttons at the floors. After the car starts, the operator should return the car switch to its central position. This will have no effect on the operation of the car because the stopping is under the control of the car buttons and the floor buttons.
- 85 When the car is operated on the preregistered signal system, it is started by moving the car
- switch to the right or left and is stopped by centering the car switch. A preregistered signal lamp SL is provided in the car and so connected to the stop push buttons that, when the car reaches a zone in which the car switch should center to stop the car at the floor for which a stop signal exists, the lamp SL will light. If the operator will center the switch at that time, the car will move into and stop level with the floor for which the signal was registered.
- 90 95 A pair of system-selecting switches 57 and 58 are provided for causing the car to operate under the preregistered signal system or under the push button control system. With switch 57 open and switch 58 disposed to engage contact member 60 as shown in Fig. 3, the system is connected for operation under the push button control system and that system will be described first.
- 100 Under the control system, when the car switch is operated to start the car, the up direction or the down direction switch which is energized completes a self-holding circuit for itself which causes it to be held in until the car approaches a floor at which a stop is to be made, at which time an automatic stopping system causes the car to slow down and stop level with the floor. The automatic stopping system is responsive to stop buttons disposed at the floors to be operated by waiting passengers who desire to have the car stop for them, and stop buttons disposed in the car for operation by the car attendant when he wants the car to stop at a floor to let off a passenger. In other words, a car is started by a car switch in the car, and is stopped by the waiting passengers pressing the stop buttons at the floors or by the attendant pressing stop buttons in the car corresponding to the floors at which stops are to be made. After the car starts the car switch may be returned to its center position to await the next starting action.
- 105 110 Any suitable system may be employed for automatically stopping the car A level with the floors it serves. As one example of such a system we have illustrated an automatic inductor relay landing system similar to that disclosed in Patent No. 1,884,446, issued October 25, 1932, to K. N. White and G. H. Hearn, and assigned to the Westinghouse Electric Elevator Company.
- 115 120 125 The landing system for car A (Fig. 1) includes a high speed decelerating inductor relay E and a stopping inductor relay F for causing the car to be automatically decelerated from its high speed and brought to a stop at exactly level with the floor. The inductor relay E is mounted on car A in position to cooperate with an inductor plate UE for the up direction and an inductor plate DE for the down direction. The inductor relay F cooperates with the inductor plate UF for the up direction, and an inductor plate DF for the down direction. The inductor plates are constructed of magnetic material and are mounted in the hatchway (not shown) in position to cooperate with and open contact members on the inductor relays when the relays are in an energized condition as the car approaches a stop at a landing.
- 130 135 140 For simplicity, only the inductor plates for one floor have been shown, but it will be understood that a set similar to that shown may be provided for each floor served by the car intermediate the upper terminal floor and the lower terminal floor. If desired, a set of inductor plates corresponding to UE and UF may be provided for the upper terminal, and a set corresponding to plates DE and DF may be provided for the lower terminal.

However, in the present instance, it will be assumed that the car will be stopped at the terminal floors by the usual and well known limit switches (not shown).

- 5 As shown, each inductor relay is provided with two sets of contact members. For an up stop, the contact members E_1 of the relay E cooperate with the inductor plate UE , and the contact members F_1 of relay F cooperate with the up 10 inductor plate UF . For the down direction, the contact members E_2 of relay E cooperate with inductor plate DE and the contact members F_2 cooperate with the inductor plate DF .

The contact members of the inductor relays 15 just described are so connected with the car control circuits that, when the inductor relays are energized to decelerate and stop the car at a floor in the down direction, the contact members E_2 pass the inductor plate DE , and are therefore opened to decelerate the car from high speed 20 to stopping speed. As the contact members F_2 come opposite the inductor plate DF , they open to stop the car level with the floor. When the stop is to be made in the up direction, the contact members E_1 are opened by the inductor plate UE and the contact members F_1 are opened by the plate UF .

The inductor relays are of the self-holding type; that is, while they are energized but have 30 not yet come opposite an inductor plate, the contact members remain closed, but when the relay comes opposite an inductor plate, the contact members adjacent that plate move to their open position and are held in such open position until 35 the inductor relay is deenergized. The means for holding the contact members in the open position of inductor relay E_2 are the extended portions 28 and 29.

For instance, it will be seen that when the inductor relay E passes the down inductor plate DE while in an energized condition, the contact members E_2 are opened by the arm 29a moving upwardly to a position where it is attracted and held by the magnetized projection 29. Therefore, the open contact members remain open and do not, after passing the inductor plate, reclose to complicate the operation of the control system. However, we do not desire to be limited to inductor relays of this particular type, because 50 inductor relays with temporary open contact members (well known in the art) may be used just as readily if the motor control system is adjusted to cooperate with them.

The exact position of the inductor plates in the 55 hatchway and of the inductor relays on the cars cannot be given here, because the position of these devices varies in each installation by reason of differences in motors, weights of cars, heights of cars, etc. However, in many commercial installations of inductor stopping systems already made, it has been found that the mechanics have no difficulty in ascertaining, while the cars are first tried out in operation, just the precise positions in which the plates and 60 relays should be placed.

An inductor maintaining relay G is provided for maintaining the inductor relays in an energized condition after they are energized until the 70 stop for which they are energized is made.

Inasmuch as the energized inductor relays remain energized after their contact members are operated by passage near the inductor plates, an inductor restoring relay H (Fig. 3) is provided 75 for deenergizing the relays after the stop is made

and also for so interlocking them that they can be energized only while the car is moving.

The energization of the inductor relays on car A for decelerating and stopping that car at the various floors is effected either by a car button 5 stopping relay S responsive to stop buttons or switches in the car, or by a floor button stopping relay T responsive to stop buttons or switches at the various floors. The energization of either the relay S or the relay T , as the car nears a 10 floor at which a stop is to be made, energizes the inductor relays on that car and thereby causes the car to decelerate and stop at that floor.

The stop push buttons in the car for energizing the relay S comprise one for each of the intermediate floors. The pressing of a car button by a car attendant will register a stop call, or in other words, initiate and maintain a circuit which will be completed by the arrival of the car within a predetermined distance of the floor corresponding to the button and thereby deenergize the stopping relay S , which will in turn energize the inductor relays to stop the car at that floor. In this manner the car may be stopped at any intermediate floor by pressing a push button in 20 the car for that floor. The push buttons in car A for the intermediate floor are designated as 2C, 3C and 4C corresponding to the second, third and fourth floors, respectively.

It will also be noted that a stop button 1C 30 is provided for the lower terminal and a stop button 5C is provided for the upper terminal. The buttons 1C and 5C are not necessary for stopping the car at the terminals because the car will stop at such terminals by the usual limit 35 switches. These buttons are provided so that the car attendant may, in accordance with our invention (as will be later described), cause the car to go to a terminal to let off a passenger at that terminal without stopping to answer a stop 40 call registered on a floor button for the opposite direction if he so desires.

The car buttons 1C to 5C are provided with holding or registering coils 1CC, 2CC, 3CC, 4CC and 5CC which operate to hold the buttons in 45 a depressed position after they are pressed by the car attendant in controlling the stops from within the car. These coils are deenergized when the car reaches the terminals to release the buttons for the next direction of operation.

The means for deenergizing the registering coils 1CC, etc., comprises an up preference relay W and a down preference relay X . These relays are controlled by the direction switches and interlocking contact members in such manner that 55 when the car starts in a direction, the preference relay for that direction will be energized, and when the car starts in the other direction, the preference relay for the other direction will be energized and the previously energized relay will 60 be deenergized. Whenever the car changes its direction, the holding coils are deenergized to restore the car buttons to their normal condition so that the car attendant may operate them for such reverse direction.

As stated previously, the floor button stopping relay T is controlled by push button switches at the floor landings, that is, the pressing of a floor button will register, or in other words, initiate and maintain a circuit which will be completed 70 as the car nears that floor and thereby energize the stop relay T , which will, in turn, energize the inductor relays to stop the car at such floor. It should be noted that, while the car buttons are individual to each car, the floor buttons are 75

common to both cars, that is, there is only an up button and a down button at each floor regardless of the number of cars. Hence the waiting passenger has only one button to press to stop the car for him in the direction in which he desires to go.

The push buttons or switches disposed at the floors for registering stop calls (see Fig. 4) are designated as follows 1UJ, 2UJ, 3UJ and 4UJ for the 10 up direction at the first, second, third and fourth floors, and 5DJ, 4DJ, 3DJ, and 2DJ for the down direction at the fifth, fourth, third and second floors. Inasmuch as no car goes below the first floor, no down button is provided for that floor, 15 and inasmuch as no car goes above the fifth floor, no up button is provided for that floor.

Associated with the floor push buttons are stop call registering relays 1UR, 2UR, 3UR and 4UR for the up direction, and 5DR, 4DR, 3DR and 20 2DR for the down direction. These relays operate to maintain a floor button circuit in a partially completed condition after the button is pressed until the car answers the registered call by stopping at the floor, so that the momentary 25 pressing of a button will effect the registration of a stop call.

A cancellation coil is also mounted upon the body of each of the call registering relays for the purpose of deenergizing and restoring that 30 relay when the call is answered. The cancellation coils are designated as 1UQ, 2UQ, 3UQ and 4UQ for the up direction, and as 5DQ, 4DQ, 3DQ and 2DQ for the down direction.

The car A is provided with a "call above" and 35 "call below" signal device for indicating to the car attendant the existence of a registered call above or below the car and that he should run the car in that direction in answer to that call. These signal devices are illustrated as a "call 40 above" panel 50 and a "call below" panel 51 disposed in front of corresponding electric lamps, so that the energization of a lamp will illuminate its panel. The "call above" lamp for car A (see Fig. 4) is designated as UL, and the "call below" 45 lamp as DL.

The "call above" relay P and the "call below" relay N are provided for controlling the "call above" and "call below" lamps UL and DL in car A. The relay P is controlled by an "above" 50 circuit 54 and the relay N is controlled by a "below" circuit 55 (Fig. 4).

The opposite direction stopping relay or opposite call response device K is provided for causing the car to stop at a floor in answer to the 55 highest down call while the car is going up and there are no higher calls, and to stop at a floor in answer to the lowest up call while the car is going down and there are no lower calls. This relay is energized and operated by the energized 60 portions of the circuits 54 and 55.

The preventing relay Y is provided to render the relay K ineffective and thus prevent the stopping of the car at the farthest call in the opposite direction when a stop call has been registered on 65 a car button. A switch 56 is disposed in the car for throwing the relay Y out of operation when desired and causing the car to operate without stopping for the farthest call in the opposite direction.

70 In order that the various circuits for the push buttons, signal devices, control relays, etc., may be connected for operation in accordance with the movements of the cars, car A is provided with a floor selector M, and a similar selector is provided for car B. The floor selectors are similar

to those usually employed in elevator signalling systems and may be located in any suitable place, such as in the penthouse.

The floor selector M for car A is provided with a set of up contact segments arranged according to the floors and disposed to be engaged by co-operating contact brushes 30, 31, 32, 33 and 34 for the up direction, and 40, 41, 42, 43 and 44 for the down direction. The brushes are mounted upon an insulated movable arm MO. The movable arm MO is operated in accordance with the movements of the car A by means of a screw shaft 52 driven by some part of the operating mechanism of the car.

The frictional engagement between the arm 15 MO and its operating screw 52 will cause the arm to bear against the up contact segments when the car is driven upwardly and against the down contacts when the car is driven downwardly, it being understood that the arm will tilt from one 20 position to the other when the direction of operation of the car is reversed. For a more complete description of floor selectors of this type, reference may be had to the Smalley and Reiners Patent No. 634,220, of October 3, 1899. If desired, electromagnets may be employed in the well known manner to tilt the arms when the cars reverse.

The group of contact segments designated as a under the up brush 30 are energized by the 30 pressing of the floor buttons for the purpose of energizing the floor button stopping relay T to stop the car on its up trip when it approaches a floor at which an up stop is to be made in response to a stop signal on the floor buttons. 35

The group of contact segments designated as b under the brush 31 are energized when stop calls are registered on the car stop buttons for the purpose of energizing the car button stopping relay S to stop the car on its up trip when it 40 approaches a floor at which an up stop is to be made in response to a stop signal on the car button.

The group of up contact segments designated as c under the brush 32 serve to connect the 45 circuits for energizing the cancellation coils on the floor button registering relays to cancel the registered floor calls when the car stops in answer thereto.

The group of contact segments designated as d under the brushes 33 and 34 serve to connect the "call above" and "call below" indicators and also for stopping the car for opposite direction calls under certain conditions.

The contact segments engaged by the down 55 brushes 40 to 44, inclusive, when the car is descending correspond to the contact segments just described for the up direction, those marked e being the floor button stopping segments, f the car button stopping segments, g the cancellation 60 segments, and h the "call above" and "call below" segments.

The up brushes 33 and 34 and the down brushes 43 and 44 leading to the "call above" and "call below" relays should be mounted upon springs 65 which will cause them to bear continuously upon their contact segments regardless of the direction of operation of the car. Also, the P and N relays in the call above and call below system should be so constructed that they will delay operation for a short period after they are deenergized. The period of delay should be short, usually only a fraction of a second, to permit the brushes 34 and 44 to cross the gap between the contact segments without operating the relays P and N. This de- 70 75 75

layed operation will prevent "flickering" of the "call above" and the "call below" lamps. The delay may be secured in any suitable manner, as by placing copper tubes in the spools upon which 5 the coils of the relays are wound.

Inasmuch as the length of the contact segments and the size of the brushes will vary in accordance with the difference in the heights of the floors, speed of the cars, etc., it is impossible to give the 10 exact dimensions of brushes and segments in this application. However, with the aid of the illustration given in Fig. 2, any one familiar with the elevator art should be able to arrange the contact segments and brushes on the floor selector to suit 15 any particular installation after the desired characteristics of the system have been ascertained.

It is believed that the invention will be understood best by an assumed operation of the system 20 diagrammatically illustrated in the drawings.

20 Operation under the button control system

It will be assumed that the switches 61 are closed to connect the supply conductors of the control circuit to a source of electrical energy, 25 that car A is standing at the third floor on an up trip and that car B is standing at the fourth floor on a down trip. With the cars at these floors, the brushes will be in the positions shown in Figs. 3 and 4.

30 The closing of the switches 61 energizes the motor field windings 19 and B19 for the motor 18 of car A and the motor B18 of car B. It will be assumed that the generators 22 and B22 are in operation and that the energized condition of the 35 motor field windings prepares the hoisting motors for operation.

With car A in the position indicated, its up direction preference relay W is energized, thereby closing its contact members W2 to maintain the 40 holding coils 1CC, 2CC, 3CC, 4CC and 5CC to maintain the car stopping push buttons 1C, etc., in car A in a depressed position if they are pressed by the car attendant to cause the car to make a stop at a floor. The down direction preference 45 relay BX for car B is also energized to close its contact members BX2, thereby energizing the holding coils B1CC, etc. for maintaining the push buttons B1C, etc. in car B in a depressed position after they are pressed by the car attendant 50 to cause that car to stop at a floor.

It will be assumed now that a waiting passenger at the second floor presses the down floor button 2DJ at that floor to stop a car for a down trip. The pressing of the button 2DJ closes its contact 55 members and thereby energizes the stop call registering relay 2DR by a circuit extending from the supply conductor L+3, the contact members of button 2DJ, coil 2DR and conductors 62 and 63 to the supply conductor L-3. The energization of the 60 registering relay 2DR registers a stop call for the next car to come to the second floor and indicates in both the cars that a stop signal exists at a floor below them, by closing its contact members 2DR1, 2DR2 and opening its contact 65 members 2DR3 and 2DR4.

The closing of the contact members 2DR1 energizes the contact segment e2 on the floor selector for car A and the contact segment Be2 on the floor selector of car B to effect the stopping of 70 the first car to arrive. The closing of the contact members 2DR2 completes a self-holding circuit for the registering relay 2DR, so that it will now stay in an energized condition until its cancellation coil 2DQ is energized. The closing of contact members 2DR2 also energizes the contact 75

segment g2 on the floor selector of car A and a contact segment Bg2 on the floor selector of car B, so that the first car to arrive and stop in answer to the call will cancel the call.

The opening of the contact members 2DR3 5 electrically disconnects a portion of the "call above" signal circuit 54, but inasmuch as both cars are above this interruption or break, it has no effect on the above signals in the cars. The opening of the contact members 2DR4 electrically 10 interrupts or breaks the "call below" circuit 55, and inasmuch as both cars are above the second floor, no current can flow from the supply conductor L+3 through the circuit 55 to the brush 15 44 of car A which, by reason of the position of car A at the third floor is now disposed on the contact segment h3. Therefore, the "below" relay N is now deenergized. This condition closes its contact members N1 and thereby energizes the "call below" lamp DL in car A by a circuit extending 20 from the supply conductor L+3 through the contact members N1 and lamp DL to the supply conductor L-3. The lighting of this lamp illuminates the "call below" panel 51 in the car A, thereby indicating to the attendant on that car that a 25 registered stop call exists at a floor below his car.

The opening of the contact members 2DR4 also deenergizes the contact segment Bh4 which is connected to the portion of the circuit 55 above the open contact members 2DR4 and thereby de- 30 energizes the brush B44 and hence the "below" relay BN for car B. The deenergization of the relay BN closes its contact members BN1 and thereby energizes the "call below" signal lamp BDL in car B by a circuit extending from the supply conductor L+4 through the contact members BN1 and lamp BDL to the supply conductor L-4. The energized lamp BDL illuminates the "call below" panel B51 in car B, thereby indicating to the 35 attendant in car B that a stop call has been registered at a floor below his car.

It will be assumed now that the attendant in car B moves the car switch BCS in a clockwise direction to start the car downwardly. The movement of the car switch closes its contact 45 members 64 and 65 thereby energizing the down direction switch BD by a circuit extending from the supply conductor L+2 (Fig. 3) through the contact members 64, 65 and BF2, the coils BD and BH and the door and gate contact members 50 B66 to the supply conductor L+2. This circuit also energizes the inductor restoring relay BH to prepare the inductor relays for operation.

The energization of the switch BD closes its contact members BD1, BD2, BD3, BD4 and BD5 55 and opens its contact members BD6. The closing of the contact members BD1 and BD3 energizes the generator field winding B23 by a circuit extending from the supply conductor L+2 through the contact members BD3, windings B23, contact 60 members BD1 and resistor Br1 to the supply conductor L+2. Energization of the generator field winding causes the generator to operate the hoisting motor B18 to rotate the hoisting drum B13 for moving car B downwardly. The closing of the 65 contact members BD2 completes a circuit for energizing the brake coil B6 to release the brake B5 by a circuit extending from the supply conductor L+2 through the winding B19, the coil B6 and the contact members BD2 to the supply conductor L+2.

The closing of the contact members BD4 energizes the high speed relay BV by a circuit extending from the supply conductor L+2 through the contact members BD4 and BF2 and the coil BV to 75

the supply conductor L-2. This relay now closes its contact members BV1 and opens its contact members BV2 and BV3. The closing of the contact members BV1 short circuits the resistor Br1 thereby causing the generator and hoisting motor to operate the car at its normal high speed. The opening of the contact members BV2 prevents energization of the stopping inductor relay BF while the car is running at high speed. The opening of the contact members BV3 (Fig. 4) prevents energization of the cancellation brushes of car B to cancel a call while the car is running at high speed.

The closing of the contact members BD5 completes a self-holding circuit for the down direction switch BD and this switch will now remain energized to keep the car moving until it is stopped by the operation of one of the stop buttons at the floor or operation of one of the stop buttons on the car. The opening of the contact members BD6 prevents energization of the up direction preference relay BW of car B while the car is going down.

The car B now moves downwardly at high speed until it approaches the second floor at which time its floor button brush 40 moves into engagement with "live" contact segment Be2 for the second floor. This engagement energizes the floor button stopping relay BT of car B by a circuit extending from the supply conductor L+1 (Fig. 3) through the contact segments 2DR1, conductor 67, contact segment Be2, brush B40, the coil BT and the contact members BH3 to the supply conductor L-2.

The energization of the relay BT closes its contact members BT1, thereby energizing the inductor relay BE and the inductor maintaining relay BG by a circuit extending from the supply conductor L+2 through the contact members BT1, switch B58, to a junction point B68 and thence in parallel through the coils BE and BG to a junction point B69 and thence through the contact members BH1 to the supply conductor L-2. The energization of the relay BG closes its contact members BG1 to maintain the inductor relays in an energized condition until after the stop is completed.

As the car B approaches still closer to the second floor, the inductor relay BE passes the down inductor plate BDE and is thereby operated to open its contact members BE2, thus deenergizing the high speed relay BV to open its contact members BV1 and close its contact members BV2 and BV3. The opening of the contact members BV1 reinserts the resistor Br1 in the circuit of the generator field winding B23, thereby slowing the hoisting motor and the car down to stopping speed. The closing of the contact members BV2 energizes the stopping inductor relay BF by placing it in parallel with the inductor relay BE. The closing of the contact members BV3 prepares the cancellation brushes for operation.

As the car B approaches more closely to the second floor at stopping speed, the energized inductor relay BF comes opposite the down stopping inductor plate BDF and is thereby operated to open its contact members BF2 to deenergize the down direction switch BD and the inductor restoring relay BH. The deenergization of the switch BD opens its contact members BD1 and BD3 in the circuit of the field winding B23 and its contact members BD2 in the circuit of the brake coil B6, thereby stopping the motor B18 and applying the brake B5 to hold the car while it stands at the second floor. The opening of

the contact members BD5 eliminates the holding circuit for the switch BD.

As car B is now standing at the second floor on its down trip, the cancellation brush B42 (Fig. 4) is disposed on the down contact segment Bg2, thereby energizing the cancellation coil 2DQ by a circuit extending from the supply conductor L+3 through the contact members 2DR2, coil 2DQ, conductor 70, contact segment Bg2, brush B42, and contact members BV3 to the supply conductor L-4. The energization of the coil 2DQ deenergizes the registering coil 2DR and thereby cancels the registered down stop call at the second floor. This cancellation will be maintained while car B stands at the second floor and will thus prevent any re-registration of a down stop call at that floor during that time.

It will be assumed now that the attendant on car B opens the car and gate (not shown), takes on the waiting down passenger, closes the door and gate, and again moves the car switch BCS in a clockwise direction. This operation will start the car downwardly as previously described, and as it comes into the lower terminal floor, the usual limit switches (not shown) will effect the stopping of the car at that terminal.

With car B at the lower terminal and car A standing at the third floor on an up trip, it will be assumed that a waiting passenger presses the down floor button 5DJ at the upper terminal or fifth floor, to register a down stop call at that floor. The closing of the button 5DJ energizes the registering relay 5DR by a circuit extending from the supply conductor L+3 through the contact members of button 5DJ and coil 5DR to the supply conductor L-3. The energization of the registering relay 5DR closes its contact members 5DR1 and opens its contact members 5DR2. The closing of the contact members 5DR1 completes a self-holding circuit for the registering relay 5DR.

The opening of the contact members 5DR2 in the circuit 54 opens the circuit for the brush 34 of call-above relay P for car A (Fig. 4), thereby deenergizing that relay. The deenergization of relay P closes its contact members P1, thereby energizing the call above lamp UL in car A by a circuit extending from the supply conductor L+3 through the contact members P1, and lamp UL to the supply conductor L-3. The lighting of lamp UL illuminates the "call above" panel 50 in car A, thereby indicating to the attendant that a call has been registered at a floor above car A.

The opening of the contact members 5DR2 in circuit 54 also deenergizes the contact segment Bd1. Therefore, the brush B34 of car B which is now standing on that contact segment, is also deenergized, thus deenergizing the call above relay BP of car B, which in turn, closes its contact members BP1, thereby energizing the call above lamp BUL in car B by a circuit extending from the supply conductor L+4 through the contact members BP1 and the lamp BUL to the supply conductor L-4. The lighted lamp BUL illuminates the "call above" panel B50 in car B, thereby indicating to the attendant in that car that a call exists at a floor above his car. Hence, it will be seen that the attendant in each car has been notified of the existence of a registered call at some floor above that car.

Inasmuch as car A is at the third floor on an up trip, it will be assumed that the car attendant moves the car switch CS in a counter-clockwise direction to start the car upwardly in search of the call above. The car will now run to and stop

at the upper terminal. The movement of the car switch CS closes its contact members 71 and 72, thereby energizing the up direction switch U by a circuit extending from the supply conductor 5 L+1 through the contact members 71 and 72, and F1, coils U and H and the door and gate contact members 66 to the supply conductor L-1.

The energization of the up direction switch U closes its contact members U1, U2, U3, U4 and 10 U5, and opens its contact members U6. The closing of the contact members U5 completes a self-holding circuit for the up direction switch U, so that it will remain energized until the car is stopped by the operation of the inductor relays. 15 Closing of the contact members U2 energizes the brake coil 6 by a circuit extending from the supply conductor L+1 through the winding 19, coil 6 and contact members U2 to the supply conductor L-1. The energized coil 6 releases the brake 20 5 to permit the starting of the car upwardly. The closing of the contact members U1 and U3 energizes the generator field winding 23 for up direction operation by a circuit extending from the supply conductor L+1 through the contact members 25 U1, winding 23, and contact members U3 and resistor r1 to the supply conductor L-1, so that the car now starts upwardly.

The closing of the contact members U4 energizes the high speed relay V to increase the speed 30 of the car B through a circuit extending from the supply conductor L+1 through the contact members U4 and E1 and the coil V to the supply conductor L-1. The energized relay V closes its contact members V1 and opens its contact members V2 and V3. The closing of the contact members V1 short circuits the resistor r1 in the generator field winding circuit, and thereby causes the car to operate at its normal high speed. The opening of the contact members V2 prevents energization of the stopping inductor relay and the opening of the contact members V3 prevents operation of the cancellation brushes of car A while it is running at high speed.

Car A is now moving upwardly at high speed 45 and as it approaches the upper terminal or fifth floor, it is slowed down and stopped at that terminal by the usual limit switches (not shown). As the car comes into and stops at the landing, the cancellation brush 32 engages the contact 50 segment c5, thereby energizing the cancellation coil 5DQ by a circuit extending from the supply conductor L+3, through the contact members 5DR1, coil 5DQ, contact segment c5, brush 32 and contact members V3 to the supply conductor L-3. The energized coil 5DQ opposes the registering coil 5DR and thereby causes the relay 5DR to open its contact members 5DR1, thereby releasing its self-holding circuit and cancelling the registered call at the upper terminal.

With the car A at the upper terminal and car B at the lower terminal, it will now be assumed that a waiting passenger at the third floor registers a down stop call by pressing the button 65 3DJ. This operation energizes the down registering relay 3DR for the third floor by a circuit extending from the supply conductor L-3 through the contact members of button 3DJ, the coil 3DR and conductors 62 and 63 to the supply conductor L-3. The energized relay 3DR closes its contact members 3DR1 and 3DR2 and opens its contact members 3DR3 and 3DR4. The closing of the contact members 3DR2 completes a self-holding circuit. The closing of the contact 70 members 3DR1 (Fig. 3) energizes the down con-

tact segment e3 of car A and down contact segment Be3 for car B for the purpose of stopping the first car serving that floor in the down direction.

The opening of the contact members 3DR3 (Fig. 4) opens the call above-below circuit 54 so that its lower portion is deenergized, thus de-energizing the contact segments d1 and Bd1. Inasmuch as the brush 34 for car B is disposed 10 on the contact segment Bd1, the call above relay BP is deenergized and therefore closes its contact members BP1, thus energizing "call above" lamp BUL. The lighting of the lamp BUL illuminates the call above panel B50 in car B, thereby indicating to the attendant in that 15 car that a registered call exists at a floor above that car.

The opening of the contact members 3DR4 interrupts the upper portion of the call below circuit 55, thereby deenergizing the contact segment h5 and the contact segment Bh5. Inasmuch as the brush 44 of car A is disposed on the deenergized contact segment h5, the call-below relay N is deenergized, and thereby closes its contact members N1 to energize the lamp DL by 25 a circuit extending from the supply conductor L+3 through the contact members N1 and lamp DL to the supply conductor L-3. The lighting of the lamp DL illuminates the "call below" panel 51 in car A, thereby indicating to the attendant in that car that a stop call is registered 30 at a floor below his car.

It will also be assumed that a waiting down passenger at the second floor, desirous of going down, presses the down button 2DR and 35 thereby registers a down stop call at the second floor in the same manner as previously described in connection with moving car B downwardly from the fourth floor. Inasmuch as the contact members 2DR3 are open in the call 40 above-below circuit 54 and the contact members 2DR4 are opened in the call above-below circuit 55, no additional effect will be added to the call-above and call-below signals in cars A and B at this time.

It will be assumed now that the attendant in car B throws the car switch BCS in a counter-clockwise direction to start his car upwardly. The movement of the switch closes its contact members 65 and 74, thereby energizing the up 50 direction switch BU to move the car upwardly by a circuit extending from the supply conductor L+2 through the contact members 65 and 74 and BF1, coils BU and BH and the contact members B66 to the supply conductor L-2.

The energization of the up direction switch BU closes its contact members BU1, BU2, BU3, BU4 and BU5 and opens its contact members BU6. The closing of the contact members BD2 releases the brake B5, as previously described. The closing of the contact members BU1 and BU3 energizes the generator field winding B23 for operating the generator and the hoisting motor B18 for the up direction. The closing of the contact members BU5 provides a self-holding circuit for the switch BU. The closing of the contact members BU4 energizes the high speed relay BV to insert the resistor Br1 in the circuit of the field winding B23 to increase the speed of the car. The energized relay BV also 65 closes its contact members BV2 and BV3 to prevent energization of the inductor relay BF and to prepare for operation of the cancellation brushes, as previously described.

The energization of the relay BH closes its 70

- contact members BH₁, BH₂, BH₃ and BH₄. The closing of the contact members BH₁ prepares the inductor relays for operation. The closing of the contact members BH₂ and BH₃ prepares the car button stopping relay BS and the floor button stopping relay BT for operation. The closing of the contact members BH₄ prepares the farthest-call-in-opposite-direction relay BK for operation.
- 10 Inasmuch as the direction of car B has been reversed by energizing the up direction switch U, the opening of the contact members BU₆ deenergizes the down direction preference relay BX which thereupon closes its contact members BX₁ and thus energizes the up direction preference relay BW by a circuit extending from the supply conductor L+2 through the contact members BD₆ and BX₁ and the coil BW to the supply conductor L-2.
- 15 20 The deenergization of the relay BS opens its contact members BX₂ and thereby deenergizes the car button holding coils B₁CC, B₂CC, etc., to release any car button upon which a call may have been registered in car B. However, the immediate energization of the relay BW closes its contact members BW₂ and thereby reenergizes the holding coils B₁CC, B₂CC, etc., so that, if the attendant presses a car button in car B during the up trip, the button will be maintained 25 in its depressed position until the car reaches the other terminal or until the direction of operation of the car is reversed.
- 25 30 Car B is now moving upwardly with its panel B₅₀ indicating a registered stop call at a floor above; that is the registered down stop call at the third floor. But as car B passes the registered down stop call at the second floor, in approaching the third floor, its energized contact brush B₄₄ engages the contact segment B_{h2}, and 35 40 is deenergized because of the open contact members 2DR₄ cutting it off from the supply conductor L+3, thereby deenergizing the call-below relay BN which in turn closes its contact members BN₁ to energize the down direction lamp BDL in car B, as previously described, to illuminate 45 the call-below panel B₅₁, thereby indicating, at this instant, that a call exists below and another call exists above car B; that is, when car is leaving the second floor, the call above-below signals 50 will indicate the call-above at the third floor and the call-below at the second floor.

It will be recalled that the contact members 3DR₃ in the circuit 54 are open in that portion of the circuit 54 immediately below the conductor 55 59 leading to the contact segments d₃ for car A and Bd₃ for car B, but that no contact members are open in that portion of circuit 54 between the supply conductor L+3 and conductor 60 64 75. Therefore, the contact segments d₃ for car A and Bd₃ for car B remain energized or "alive". As car B runs up and approaches the third floor, its "farthest stop brush" B₃₃ slips off the "dead" contact segments and upon the "live" contact segment Bd₃ and thereby energizes the relay BK 65 70 to effect the stopping of the car B at the third floor for the down call at that floor, even though car B is running in the up direction. The circuit for relay BK extends from the supply conductor L+3 through conductor 54, the contact members 5DR₂, 4UR₃, 4DR₃, 3UR₃, conductors 75 and 76, contact segment Bd₃, brush B₃₃, contact members BY₁, coil BK and the contact members BH₄ to the supply conductor L-4.

The energization of the relay BK to stop the car closes its contact members BK₁, and thereby

energizes the inductor relay BE by a circuit extending from the supply conductor L+2 through the contact members BK₁, switch B₅₃, coil BE, and contact members BH₁ to the supply conductor L-2.

As the car continues to approach upwardly toward the third floor, the energized inductor relay BE passes the up inductor plate BUE for the third floor and is thereby energized to open its contact members BE₁ to deenergize the high speed relay BV which, in turn, opens its contact members BV₁ to reinsert the resistor Br₁ in the generator circuit thereby decelerating the car. The deenergized high speed relay BV also closes contact members BV₂, thereby energizing the inductor relay BF, and closes its contact members BV₃ to prepare the cancellation brushes for operation, as previously described.

As the car approaches still closer to the third floor, the energized inductor relay BF passes the stopping inductor plate BUF, and is thereby operated to open its contact members BF₁, thus deenergizing the up direction switch BU to stop the car level with the third floor.

The deenergization of the switch BU opens its contact members BU₁, BU₂, BU₃, BU₄ and BU₅ and closes its contact members BU₆. The opening of the contact members BU₂ deenergizes the brake coil B₆ to apply the brake B₅ to the hoisting motor. The opening of the contact members BU₁ and BU₃ opens the generator field winding B₂₃ to stop the motor, and the opening of the contact members BU₅ breaks its self-holding circuit and the car now stands at the third floor.

By reason of the foregoing, it is seen that car B, although it is travelling in the up direction and has no stop calls registered for the up direction on either the floor buttons or its car buttons, has stopped at the floor of the highest registered down call.

Also, it will be seen that as car B leaves the second floor its brush B₃₄ leaves segment Bd₂ and engages segment Bd₃ and is thereby energized by a circuit from L+3 through contacts 5DR₂, 4UR₃, 4DR₃, 3UR₃, conductors 75 and 76 to segment Bd₃, brush B₃₄ and coil BP to conductor L-4. The energization of relay BP extinguishes the call above lamp BUL in car B.

Inasmuch as the car B is now stopped at the third floor and is taking on a passenger for a down trip, the car attendant will throw the car switch ECS in a clockwise direction to start the car downwardly by energizing the down direction switch BD as previously described.

As the car reverses its direction, the up brushes 55 on its floor selector leave the up contact segments and the down brushes engage the down contact segments for the down trip. As the down brush 42 engages the down contact segment g₃, the cancellation coil 3DQ is energized to cancel the down call at the third floor by a circuit extending from the supply conductor L+3 through the contact members 3DR₂, coil 3DQ, conductor 77, contact segment Bg₃, brush B₄₂ and the contact members BV₃ to the supply conductor L-4, the opening of the contact members BV₃ being retarded by the dashpot 85. The energization of the coil 3DQ will oppose the energized coil 3DR and thereby deenergizing the registering relay 3DR to cancel the registered down 60 call at the third floor and to close its contact members 3DR₃ and 3DR₄ in the call-above call-below circuits 54 and 55 to eliminate the "call below" signal given in car A by the registered down call at the third floor. It will also prevent 65 70 75 80 85 90 95 99

the illumination of the call above-below signal in car B as that car leaves the third floor.

As the car B starts downwardly, it will pick up the registered down call at the second floor, make 5 the stop, and then proceed to the lower terminal floor, as described in connection with the previously registered down call at the second floor.

Hence it is seen that although car B started on an up trip, it was stopped at the floor at which 10 the most distant call was registered in the opposite direction.

With car A at the upper landing and car B now at the lower landing, it will be assumed that a passenger enters car B and indicates a desire to 15 get off at the fourth floor. Thereupon, the attendant in car B presses the car button B4C to register a car call for a stop at the fourth floor. The pressing of the button closes its contact members B4C2, thereby energizing the up contact 20 segment Bb4 to effect the stopping of car B when it arrives at the fourth floor on its next up trip. Inasmuch as the holding coil B4CC is energized, the button B4C will remain in its depressed or registered condition until the direction 25 of operation of the car is reversed.

The opening of the contact members B4C1 of the pressed button makes a break in the circuit leading to the preventing relay BY to prevent the car B from answering the uppermost call in 30 the opposite or down direction below the fourth floor, while it is going up to the fourth floor. The energization of the relay BY opens its contact members BY1 (Fig. 4) in the circuit leading to the last call stopping relay BK. Hence, the relay 35 BK cannot be energized to effect the stopping of the car B as long as the contact members BY1 are open.

It will be assumed now that a waiting passenger 40 presses the down button 3DJ at the third floor, thereby registering a down stop call at the third floor on the registering relay 3DR, as previously described. This registration operates the "call above" signal in car B and the "call below" signal in car A. It also deenergizes that part of the 45 circuit 54 below the conductor 75, thus leaving the contact segment Bd3 in an energized condition from its connection with the supply conductor L+3 through the upper part of circuit 54.

It will also be assumed that the attendant 50 in car B moves the car switch BCS in a counter-clockwise direction thereby energizing the up direction switch BU to run car B upwardly, as previously described. As car B runs upwardly, its up brush B33 engages the energized contact segment Bd3, but the last call stopping relay BK is 55 not energized in this instance because the contact members BY1 in its circuit have been opened by the registration on the car button B4C of the stop call for the fourth floor.

60 As car B continues upwardly, its brush B31 engages the energized contact segment Bb4 and thereby energizes the car button stopping relay BS to stop the car at the fourth floor, by a circuit extending from the supply conductor L+2 65 through the contact members B4C2, contact segment Bb4, brush B31, coil BS and contact members BH2 to the supply conductor L-2. The energized relay BS closes its contact members BS1, thereby energizing the inductor relay BE 70 by a circuit extending from the supply conductor L+2 through the contact members BS1, switch B52, coil BE and contact members BH1 to the supply conductor L-2. As the car B approaches the 75 fourth floor, the energized inductor relay BE passes the up inductor plate BUE and is thereby

operated to open its contact members BE1, thus deenergizing the high speed relay BV. The deenergized high speed relay BV decelerates the car and effects the energization of the stopping inductor relay BF, as previously described. 5

As the car B approaches still more closely to within stopping distance of the fourth floor, the energized inductor relay BF passes the inductor plate UF and is thereby operated to open its contact members BF1, thus deenergizing the up direction switch BU and effecting the stopping of the car, as previously described, at the fourth floor. 10

From the above, it will be seen that the registration of a stop call upon a car button for a floor 15 beyond the farthest call in the opposite direction will result in the car passing the registered call in the opposite direction without stopping.

It will also be seen that if the switch 56 leading to the preventing relay Y and the switch B56 20 leading to the preventing relay BY are opened and left in that condition, the cars may be operated without responding to the farthest call in the opposite direction. That is, they may be operated in the regular manner with the call 25 above and call below signals working but without stopping for any call in the opposite direction.

Operation under the preregistered signal system

The system will be changed now to operate 30 under the preregistered signal system instead of under the button control system. This change is effected by closing the switch 57 to connect the contact member 82 of the car switch CS directly to the inductor relays so that if the car switch is 35 centered after being moved to the right or to the left to start the car, the inductor relays will be energized to stop the car at the next floor. In other words, if the attendant in the car throws the car switch while within a predetermined distance from a floor, the inductor relays will be 40 energized to automatically decelerate the car and stop accurately level with that floor in the same manner as when operating under push button control. The switch 58 is also moved from the 45 contact member 60 to contact member 59, thereby disconnecting the contact members K1, S1 and T1 from the circuit of the inductor relays and connecting them to the circuit of the preregistered signal lamp SL in car A. Also, switch B58 is 50 thrown from the contact member B60 to the contact member B59 and the switch B57 is closed to change the circuits for car B in the same manner as they have been changed for car A so that car B will operate under the lighting of the preregistered signal lamp BSL in that car instead of 55 under the push button control.

It will now be assumed that car B is returned to the lower terminal and that a waiting passenger at the fourth floor registers an up call by 60 pressing the button 4UJ at the fourth floor to light the stop signal lamp in the first car for the up direction. The pressing of the button energizes the registering relay 4UR by a circuit extending from supply conductor L+3 through the 65 contact members of button 4UJ, the coil 4UR and the conductors 62 and 63 to the supply conductor L-3.

The energization of the registering relay 4UR closes its contact members 4UR1 and 4UR2 and 70 opens its contact members 4UR3 and 4UR4. The closing of the contact members 4UR2 establishes a self-holding circuit for the relay. The closing of the contact members 4UR1 energizes 75 the contact segment a3 on the floor selector of car 75

A and the contact segment **Ba3** on the floor selector of car B so that the first car to arrive at the fourth floor in the up direction will have its preregistered signal operated to indicate a stop at the fourth floor.

The opening of the contact members **4UR3** in the call above circuit **54** cuts off the lower portion of that circuit from being energized by the supply conductor **L+3** thereby deenergizing the contact segments **d1** and **Bd1**. Inasmuch as car B is standing at the lower terminal and its brush **B34** is disposed on the deenergized contact segment **Bh1**, the "call above" relay **BP** is deenergized and thereby closes its contact members **BP1** to energize the call above lamp **BUL** in car B. The lighting of the lamp **BUL** illuminates the call above panel **B50** in car B, thereby indicating to the attendant in that car the existence of a call at a floor above the car. The opening of the contact members **4UR4** in the call below circuit **55** deenergizes the upper portion of that circuit, thus deenergizing the contact segment **h5** upon which the brush **44** of car A is disposed. This deenergizes the relay **N** to close its contact members **N1**, thus energizing the call below lamp **DL**. The lighting of the lamp **DL** illuminates the call below panel **51** in car A, thereby indicating to the car attendant in that car the existence of a registered call at a floor below that car.

It will also be assumed that a waiting passenger at the third floor, desirous of making a down trip, presses the down button **3DJ**, thereby registering a down stop call at the second floor, as previously described in connection with the control system. The registration of the down stop call at the third floor energizes the down contact segment **e3** on the floor selector of car A and the down contact segment **Be3** on the floor selector of car B for the purpose of giving a stop signal to the first car serving that floor in the down direction.

It will be assumed now that the attendant in car B throws the car switch **BCS** in a counter-clockwise direction and starts car B on an up trip, as previously described. As car B moves upwardly, it passes the down stop call registered at the third floor. Although that call is registered for the opposite direction, it is not the farthest call in the direction car B is going because of the existence of the up registered call at the fourth floor. As stated above, the up registered call at the fourth floor has opened the contact members **4UR3** in the circuit **54** and the contact members **4UR4** in the circuit **55**. Therefore, although the brush **B33** of car B engages the contact segment **Bd3** connected with circuit **54** as the car goes up, the farthest call stopping relay **BK** will not be energized because of the open contact members **4UR3** above the point at which the conductor **75** from the contact members **Bd3** is connected to the conductor **54**. Hence, car B will not receive a stop signal at this call in the opposite direction but will continue moving toward the fourth floor.

As car B approaches the fourth floor, its brush **B30** engages the energized contact segment **Ba4**, thereby energizing the floor button stopping relay **BT** to give a stop signal, by a circuit extending from the supply conductor **L+1** through the contact members **4UR1**, contact segment **Ba4**, brush **B30**, coil **BT** and the contact members **BH3** to the supply conductor **L-2**. The energization of the relay **BT** closes its contact members **BT1** thereby lighting the signal lamp **BSL** in car B by a circuit extending from the supply conductor **L+2** through the contact members **BT1**, switch **B58**,

contact members **B59**, lamp **BSL** and the contact members **BH1** to the supply conductor **L-2**.

The lighting of the signal lamp **BSL** in car B gives the preregistered signal to the car attendant, thereby indicating to him that he should immediately center the car switch **BCS** to stop the car at the next floor. The attendant immediately centers the car switch and thereby energizes the inductor relay **BE** and the inductor maintaining relay **BG** by a circuit extending from the supply conductor **L+2** through the contact members **65** and **80** of switch **BCS**, the now closed switch **B51** and thence in parallel through the coils **BE** and **BG** to the junction point **B69** and through the contact members **BH1** to the supply conductor **L-2**.

As car B approaches still closer to the fourth floor, the energized inductor relay **BE** passes the up inductor plate **BUE**, and is thereby energized to open its contact members **BE1** thus deenergizing the high speed relay **BV** to open its contact members **BV1** and close its contact members **BV2** and **BV3** to effect deceleration of the car, the energizing of the stopping inductor relay **BF** and the preparation of the cancellation brushes, as previously described.

As the car approaches to within stopping distance of the fourth floor, the energized inductor relay **BF** comes opposite the up inductor plate **BUF** and is thereby operated to open its contact members **BF1**, which deenergizes the up direction switch **BU** and stops the car level with the fourth floor in the same manner as previously described in connection with the other floors.

It will be assumed now that a waiting passenger at the second floor, desirous of going up, presses the up button **2UJ** and thereby registers an up stop call at the second floor. The pressing of the button energizes the registering relay **2UR** by a circuit extending from the supply conductor **L+3** through the contact members of button **2UJ**, the coil **2UR** and conductors **62** and **63** to the supply conductor **L-3**. The energized relay **2UR** closes its contact members **2UR1** and **2UR2** and opens its contact members **2UR3** and **2UR4**. The closing of the contact members **2UR2** provides a self-holding circuit for the relay. The closing of the contact members **2UR1** energizes the contact segment **a2** on the floor selector of car A and the contact segment **Ba2** on the floor selector of car B for the purpose of giving a stop signal to the first car approaching in the up direction.

The opening of the contact members **2UR3** in call above circuit **54** and the contact members **2UR4** in circuit **55** do not affect the call above signals in either car as both cars are above the second floor.

It will be assumed now that the attendant in car A moves the car switch **CS** in a clockwise direction, thereby energizing the down direction switch to run car A downwardly in the same manner as has been described in connection with car B.

As car A approaches the third floor in the down direction, its contact brush **40** engages the contact segment **e3** (energized by the registered down stop at the third floor) and will thereby energize the floor button stopping relay **T** by a circuit extending from the supply conductor **L+1** through the contact members **3DR1**, contact segment **e3**, brush **40**, coil **T**, and contact members **H3** to the supply conductor **L-1**.

The energized relay **T** closes its contact members **T1** thereby lighting the preregistered signal lamp **SL** by a circuit extending from the supply

conductor L+1 through the contact members T1, switch 58 (now closed to contact member 59) the lamp SL and contact members H1 to supply conductor L-1. The lighting of the lamp SL indicates to the attendant in car A that he should at once throw his car switch CS to its central position. Assuming that he does this, he thereby energizes the inductor stopping relay E and the inductor maintaining relay G by a circuit 10 extending from the supply conductor L+1 through the contact members 11 and 82 of switch CS, the now closed switch 57, in parallel through the coils E and G and then through the contact members H1 to the supply conductor L-1. As 15 the car approaches more closely to the third floor, the energized inductor relay system stops level with the floor in the same manner as described in the operation of car B. It will be assumed that the attendant in car A opens the car gate and 20 door (not shown) and takes on the waiting passenger, and starts the car to continue its down trip. As car A proceeds downwardly, it approaches the second floor at which is registered the up stop call. Inasmuch as this is the lowest 25 call for car A going downwardly even though the call is in the opposite direction, it will effect the giving of the preregistered stopping signal to the attendant in car A so that he can stop the car at that floor.

As car A approaches within signalling distance of the second floor, its brush 43 engages the contact segment h2 and thereby energizes the last call stopping relay K by a circuit extending from the supply conductor L+3 through conductor 83, 30 contact members 1UR2 and 2DR4, conductor 84, contact segment h2, brush 43, contact members Y1, coil K and contact members H4 to the supply conductor L-3. The energization of the relay K closes its contact members K1 (Fig. 3) thereby 35 energizing the preregistered signal lamp SL by a circuit extending from the supply conductor L+1 through the contact members K1, switch 58, (now on contact member 59), lamp SL and the contact members H1 to the supply conductor L-1. The lighting of the lamp SL indicates to the attendant in car A that he should immediately center the car switch CS to stop the car at the next floor. It will be assumed now that the car attendant centers the car switch 45 and stops the car at the second floor, as previously described in stopping this car at the third floor.

Inasmuch as car A has now no calls below the second floor and the passenger for whom he 50 stopped at the second floor desires to make an up trip, the attendant on car A will now start that car upwardly by moving the car switch CS in a counter-clockwise direction, thereby energizing the up direction switch U and moving the 55 car upwardly, as previously described.

The change in direction of operation of the car will cause the down brushes on the floor selector of car A to be lifted from the down contact segments and the up brushes to engage the 60 up contact segments. Hence the "up" cancelling brush 32 will now engage the up contact segment c2 and thereby energize the cancellation coil 2UQ by a circuit extending from the supply conductor L+3 through the contact members 65 2UR2, coil 2UQ, contact segment c2, brush 32, and contact members V3 to the supply conductor L-3. The energization of the cancellation coil 2UQ opposes the energized coil 2UR and thereby 70 restores the registering relay 2UR to its inactive 75 position, thus cancelling the up call at the second

floor and restoring the call above and call below signals into the cars now that car A has answered the lowest call in the opposite direction.

By reason of the foregoing description, it will be seen that we have provided a flexible elevator 5 system which may be operated under either a push button control system or a preregistered signal system to answer, in the most effective manner, the stop calls of the passengers regardless of the direction of the calls and the direction of 10 movement of the cars so that all the cars may operate at the points in the system where they may render the most efficient service.

Although we have illustrated and described only two applications of our invention, it is to be 15 understood that many changes and modifications may be made therein without departing from the spirit and scope of the invention.

We claim as our invention:

1. In an elevator system for operating a car 20 serving a plurality of floors, an up call registering device and a down call registering device for each floor, a signal device in the car, means responsive to the operation of a call registering device for operating the signal device in the car to indicate 25 whether the call is at a floor above or below the car, means for starting the car, a stopping means for the car, means responsive to the approach of the car to a registered call in the corresponding direction for stopping the car at that floor, and 30 means responsive to the approach of the car to a registered call in the opposite direction for stopping the car at that floor provided no more distant call exists in the direction of operation 35 of the car.

2. In an elevator system for operating a plurality of cars serving a plurality of floors, an up call registering device and a down call registering device for each floor, a signal device in each car, means responsive to the registration of one or 40 more calls for operating the signal device in each car to indicate the direction of the floors of the registered calls from that car, starting means for the cars, a stopping means for each car, and means responsive to the position of the first car 45 to approach the most distant registered call regardless of the direction of that registered call for operating the stopping means of that car to stop it at the floor of that registered call.

3. In an elevator system for operating a car 50 serving a plurality of floors, an up call registering device and a down call registering device for each floor, an energized "above" circuit and an energized "below" circuit, means responsive to registration of an up call and/or down call for deenergizing that portion of the "above" circuit corresponding to the floors below the registered call and for deenergizing that portion of the "below" circuit corresponding to the floors above the car, a signal device on the car, means responsive to the 55 deenergized portions of the "above" and "below" circuits for operating the signal device in the car to indicate whether the registered call is at a floor above or below the car, means for starting the car, a stopping means for the car, means responsive to 60 the approach of the car to the registered call in the corresponding direction for operating the stopping means to stop the car, and means responsive to the energized portions of the "above" and "below" circuits for operating the stopping 65 means to stop the car at the most distant registered call for the opposite direction when no farther call is registered in the direction the car is running.

4. In an elevator system for operating a plu- 75

- rality of cars serving a plurality of floors, an up call registering device and a down call registering device for each floor, an energized "above" circuit and an energized "below" circuit, means responsive to the registration of one or more calls for deenergizing that portion of the "above" circuit corresponding to the floors below the registered call or calls and for deenergizing that portion of the "below" circuit corresponding to the floors above the registered call or calls, a signal device in each car, means responsive to the deenergized portions of the said circuits for operating the signal device to indicate the direction of the floor of the registered call from each of the cars, means for starting the cars, individual stopping means for the cars, means responsive to the registered calls for operating the stopping means of the first car to approach in the corresponding direction, and means responsive to the energized portions of the said circuits for stopping the first car to approach a registered call in the opposite direction when it is the farthest registered call in the direction of operation of that car.
5. In an elevator system for operating a car serving a plurality of floors, an up call registering switch and a down call registering switch at each floor, a stop call registering device in the car, an energized "above" circuit and an energized "below" circuit, means responsive to the registration of a call on a switch for deenergizing that portion of the "above" circuit corresponding to the floors below the registered call and for deenergizing that portion of the "below" circuit corresponding to the floors above the registered call, a signal device in the car, means responsive to the deenergized portions of said circuits for operating the signal device to indicate the direction of the floor of the registered call relative to the car, means for starting the car, a stopping means for the car, an opposite call device, means responsive to the energized portions of the said circuits for energizing the opposite call device to operate the stopping means to stop the car at the floor of the registered call as it approaches said registered call in a direction opposite to the direction of that registered call when no more distant call exists in the direction of operation of the car and means responsive to the registration of a call on the registering device in the car for preventing operation of the opposite call device.
6. In an elevator system for operating a car serving a plurality of floors, means for starting the car, a stopping means for the car, an up control device and a down control device for each floor, an energized "above" circuit and an energized "below" circuit, means responsive to operation of a control device for deenergizing that portion of the "above" circuit corresponding to the floors below the floor of the operated control device and for deenergizing that portion of the "below" circuit corresponding to the floors above the floor of the operated control device, an opposite call device responsive to connection with the energized portion of the "above" circuit as the car travels upwardly for operating the stopping means to stop the car at the next floor and responsive when traveling downwardly to connection with the energized portion of the "below" circuit for operating the stopping means to stop the car at the next floor.
7. In an elevator system for operating a plurality of cars serving a plurality of floors, means for starting the cars, a stopping means for each car, an up control device and a down control device at each floor common to all the cars, an energized "above" circuit and an energized "below" circuit common to all the cars, means responsive to the operation of a control device at a floor for deenergizing that portion of the "above" circuit corresponding to the floors below the floor of the operated control device and for deenergizing that portion of the "below" circuit corresponding to the floors above the floor of the operated control device, an opposite call device for each car for operating the stopping device of that car, and means responsive to the approach of the first car to the energized portion of that circuit corresponding to the direction of that car for connecting the opposite call device of that car to that energized circuit whereby the stopping of that car will be effected at the next floor in the direction of operation of that car.
8. In an elevator system for operating a car serving a plurality of floors, means for starting the car, a stopping means for the car, an up control device and a down control device at each floor, means responsive to operation of the control device and to the approach of the car in the corresponding direction for stopping the car at the floor of the operated control device, an energized "above" circuit and an energized "below" circuit, means responsive to operation of the control devices to register stop calls for deenergizing that portion of the "above" circuit corresponding to the floors below, the operated control device and for deenergizing that portion of the "below" circuit corresponding to the floors above the operated control device, an opposite call device responsive to the energized portion of the "above" circuit when the car makes an up trip and to the energized portion of the "below" circuit when the car makes a down trip for operating the stopping means of the car when it arrives at the floor of an operated control device for the opposite direction and no operated control device exists beyond that floor in the direction of travel of the car.
9. In an elevator system for operating a car serving a plurality of floors, means for starting the car, a stopping means for the car, an up control device and a down control device at each floor, means responsive to operation of the control device and to the approach of the car in the corresponding direction for stopping the car at the floor of the operated control device, an energized "above" circuit and an energized "below" circuit, means responsive to operation of the control devices to register stop calls for deenergizing that portion of the "above" circuit corresponding to the floors below, the operated control device and for deenergizing that portion of the "below" circuit corresponding to the floors above the operated control device, an opposite call device responsive to the energized portion of the "above" circuit when the car makes an up trip and to the energized portion of the "below" circuit when the car makes a down trip for operating the stopping means of the car when it arrives at the floor of an operated control device for the opposite direction and no operated control device exists beyond that floor in the direction of travel of the car, and means responsive to the manual operation of the car attendant for rendering said opposite call device ineffective when the attendant does not desire to make a stop for the farthest call in the opposite direction.
10. In an elevator system for operating a car serving a plurality of floors, means for starting the car, a stopping means for the car, an up control device and a down control device at each

- floor, means responsive to operation of a control device for operating the stopping means when the car approaches in the corresponding direction, an energized "above" circuit and an energized "below" circuit, means responsive to operation of a control device for deenergizing that portion of the "above" circuit corresponding to the floors below the operated control device, and for deenergizing that portion of the below circuit corresponding to the floors above the operated control device, an opposite call device responsive to the "above" and "below" circuits and to the approach of the car to the floor of the most distant operated control device when it is for the opposite direction for stopping the car at that floor, control devices disposed in the car for registering stop calls to be made at the floors, and means responsive to the registration of a stop call on a control device in the car for rendering ineffective the opposite call device.
11. In an elevator system for operating a car serving a plurality of floors, means for starting the car, means for stopping the car, an up control device and a down control device at each floor, means responsive to operation of a control device for operating the stopping means when the car approaches in the direction of the operated control device, an energized "above" circuit and an energized "below" circuit, means responsive to operation of a control device for deenergizing that portion of the "above" circuit corresponding to the floors below the operated control device and for deenergizing that portion of the "below" circuit corresponding to the floors above the operated control device, an opposite call device responsive to the energized portions of the "above" and "below" circuits for operating the stopping means of the car as it approaches the floor of the most distant operated control device for the opposite direction, and means responsive to reversal of the car after making the opposite direction stop for restoring the operated opposite direction control device to normal condition.
12. In an elevator system for operating a car serving a plurality of floors, means for starting the car, an up control device and a down control device at each floor, a call response device responsive to operation of a control device and to the approach of the car in the corresponding direction for operating a means associated with the stopping of the car, an energized "above" circuit and an energized "below" circuit, means responsive to operation of a control device for deenergizing that portion of the "above" circuit corresponding to the floors below the operated control device and for deenergizing that portion of the "below" circuit corresponding to the floors above the operated control device, and an opposite call response device responsive to the energized portion of the "above" circuit when the car moves upwardly for operating a means associated with the stopping of the car as the car arrives at the highest operated down control device while no farther up control device is operated and responsive to the energized portion of the "below" circuit while the car is travelling downwardly for operating a means associated with the stopping of the car as the car arrives at the lowest operated up control device while no farther down control device is operated.
13. In an elevator system for operating a car serving a plurality of floors, means for starting the car, an up control device and a down control device for each floor, an energized "above" circuit and an energized "below" circuit, means responsive to energization of a control device for deenergizing that portion of the "above" circuit corresponding to the floors below the floor of the operated control device and for deenergizing that portion of the "below" circuit corresponding to the floors above the floor of the operated control device, a pre-registered signal device and a stopping device, an opposite call response device for operating either the pre-registered signal device or the stopping device, means for selectively connecting the pre-registered signal device or the stopping device to the opposite call response device, and means responsive to upward travel of the car for connecting the opposite call response device to the energized portion of the "above" circuit and to downward travel of the car to connect the opposite call response device to the energized portion of the "below" circuit for operating the call responding device.
14. In an elevator system for operating a car serving a plurality of floors, means for starting the car, an up control device and a down control device at each floor, a call responsive device responsive to operation of a control device and to the approach of the car in the corresponding direction for operating some means functionally related to the stopping of the car, an energized "above" circuit and an energized "below" circuit, means responsive to operation of a control device for deenergizing that portion of the "above" circuit corresponding to the floors below the operated control device and for deenergizing that portion of the "below" circuit corresponding to the floors above the operated control device, an opposite call response device responsive to the energized portion of the "above" circuit when the car moves upwardly for operating some means functionally related to the stopping of the car as the car arrives at the highest operated down control device while no farther up control device is operated and responsive to the energized portion of the "below" circuit while the car is traveling downwardly for operating some means functionally related to the stopping of the car as it arrives at the lowest operated up control device and no farther down control device is operated, and means responsive to reversal of the car upon answering an opposite direction operated control device for restoring that operated control device to its normal condition.
15. In an elevator system for operating a plurality of cars serving a plurality of floors, an up call registering device and a down call registering device for each floor, a call "above-below" signal device in each car, means responsive to the operation of a call registering device for operating the call "above-below" signal device in each car to indicate whether the call is above or below that car, means for starting the cars, a call responsive means for each car responsive to the approach of that car to a registered call in a corresponding direction for operating some device functionally related to the stopping of that car at that floor, and an opposite call responsive device for each car responsive to the approach of that car to a registered call in the opposite direction for operating some device functionally related to the stopping of that car at the floor of that call provided no more distant call exists in the direction of operation of that car.
16. In an elevator system for operating a car serving a plurality of floors, an up call registering device and a down call registering device for each floor, a call "above-below" signal device in the car, means responsive to the operation of a

- call registering device for operating the call "above-below" signal device in the car to indicate whether the call is above or below the car, means for starting the car, a call response means 5 responsive to the approach of the car to a registered call in a corresponding direction for operating some device associated with the car for stopping the car at that floor, and an opposite call response device responsive to the approach 10 of the car to a registered call in the opposite direction for operating some device associated with the stopping of the car at the floor of that call provided no more distant call exists in the direction of operation of the car.
- 15 17. In an elevator system for operating a plurality of cars serving a plurality of floors, an up call registering device and a down call registering device for each floor, a call "above-below" signal device in the car, means responsive to the 20 operation of a call registering device for operating the call "above-below" signal device in the car to indicate whether the car is at the floor above or below the car, means for starting the car, a stopping means for the car, a pre-registered signal device on the car for indicating when the attendant should operate the stopping means to stop the car in answer to an operated control device, means responsive to the approach of the car to a registered call in the corresponding direction for operating the pre-registered signal device, and means responsive to the approach of the car to a registered call in the opposite direction for operating the pre-registered signal device provided no more distant call exists in the direction 25 of operation of the car.
- 30 18. In an elevator system for operating a car serving a plurality of floors, an up call registering switch and a down call registering switch at each floor, an energized "above" circuit and an energized "below" circuit, means responsive to the registration of a call on a switch for de-energizing that portion of the "above" circuit corresponding to the floors below the registered call and for deenergizing that portion of the 35 "below" circuit corresponding to the floors above the registered call, a call "above-below" signal device in the car, means responsive to the de-energized portions of said circuits for operating the call "above-below" signal device to indicate the direction of the floor of the registered call relative to the car, means for starting the car, a stopping means for the car, an opposite call response device, means responsive to the energized portions of the said circuits for energizing the opposite call response device as the car approaches said registered call in a direction opposite to the direction to that registered call when no more distant call exists in the direction of operation of the car, a pre-registered signal device in the car, and means responsive to operation 40 of the opposite call responding device for operating the pre-registered signal device to indicate to the car attendant to operate the car stopping means.
- 45 19. In an elevator system for operating a car serving a plurality of floors, means for starting the car, a stopping means for the car, a pre-registered signal device in the car for indicating when the attendant should operate the stopping means to stop the car in answer to an operated control device, an up control device and a down control device at each floor, means responsive to operation of a control device and to the approach of the car to the floor of the operated control device in the corresponding direction for operating some means functionally related to the stopping of the car, an energized "above" circuit and an energized "below" circuit common to all the cars, means responsive to operation of a control device for deenergizing that portion of the "above" circuit corresponding to the floors below the operated control device and for deenergizing that portion of the "below" circuit corresponding to the floors above the operated control device, an opposite call response device for each car responsive to the energized portion of the "above" circuit when that car moves upwardly for operating some means functionally related to the stopping of the car as the car arrives at the highest operated down control de- 50
- 55 20. In an elevator system for operating a car serving a plurality of floors, means for starting the car, a stopping means for the car, a signal device in the car for indicating when the attendant should operate the stopping means to stop the car in answer to an operated control device, an up control device and a down control device at each floor, means responsive to operation of a control device and to the approach of the car in the corresponding direction for stopping the car at the floor of the operated control device, an energized "above" circuit and an energized "below" circuit, means responsive to operation of a control device for deenergizing that portion of the "above" circuit corresponding to the floors below the operated control device and for deenergizing that portion of the "below" circuit corresponding to the floors above the operated control device and opposite direction control means responsive to the energized portion of the "above" circuit when the car moves upwardly for operating the signal device as the car arrives at the highest operated down control device while no farther up control device is operated and responsive to the energized portion of the "below" circuit while the car is traveling downwardly for operating the signal device as the car arrives at the lowest operated up control device and no farther down control device is operated.
- 60 21. In an elevator system for operating a plurality of cars serving a plurality of floors, means for starting each car, an up control device and a down control device at each floor, a call responsive device for each car and responsive to operation of a control device and to the approach of that car to the floor of the operated control device in the corresponding direction for operating some means functionally related to the stopping of the car, an energized "above" circuit and an energized "below" circuit common to all the cars, means responsive to operation of a control device for deenergizing that portion of the "above" circuit corresponding to the floors below the operated control device and for deenergizing that portion of the "below" circuit corresponding to the floors above the operated control device, an opposite call response device for each car responsive to the energized portion of the "above" circuit when that car moves upwardly for operating some means functionally related to the stopping of the car as the car arrives at the highest operated down control de- 65
- 70 75

vice while no farther up control device is operated and responsive to the energized portion of the "below" circuit while that car is travelling downwardly for operating some means functionally related to the stopping of the car as it arrives at the lowest operated up control device and no farther down control device is operated, and means responsive to reversal of a car upon answering an opposite direction operated control device for restoring that operated control device to its normal condition.

22. In an elevator system for operating a plurality of cars serving a plurality of floors, an up call registering device and a down call registering device for each floor, means for starting the cars, a stopping means for each car, and means responsive to the position of the first car to approach the most distant registered call regardless of the direction of that registered call for operating the stopping means of that car to stop it at the floor of that registered call.

23. In an elevator system for operating a plurality of cars serving a plurality of floors, an up call registering device and a down call registering device for each floor, an energized "above" circuit and an energized "below" circuit, means responsive to the registration of one or more calls for deenergizing that portion of the "above" circuit corresponding to the floors below the registered call or calls and for deenergizing that portion of the "below" circuit corresponding to the floors above the registered call or calls, means for starting the cars, individual stopping means for the cars, means responsive to the registered calls for operating the stopping means of the first car to approach in the corresponding direction, and means responsive to the energized portions of the said circuits for stopping the first car to approach a registered call in the opposite direction when it is the farthest registered call in the direction of operation of that car.

24. In a control system for a plurality of elevator cars serving a plurality of floors, means for starting the cars, an up control device and a down control device at each of said floors, means individual to each car and responsive to the operation of either control device at one of the floors to stop the associated car at said floor, means for causing the operation of the stopping means for but one of the cars approaching the floor, said means effective to stop said car regardless of its direction of travel provided no other control device is operated at any floor beyond said floor in the direction of travel of said car, and means for preventing the operation of the stopping means for the other cars in response to said operated control device until after the first-named car has stopped at the floor.

25. In a control system for a plurality of elevator cars serving a plurality of floors, means for starting the cars, an up control device and a down control device at each of said floors, means responsive to the operation of an up control device at one of the floors to stop one of said cars depending on the relative positions of said cars, said means effective to stop said car

regardless of its direction of travel provided no other control device is operated at any floor beyond said floor in the direction of travel of said car, and means for preventing the stopping of the other cars at said floor in response to the operation of said up control device until after the first-named car has stopped at said floor.

26. In an elevator system for operating a plurality of cars serving a plurality of floors, an up call registering device and a down call registering device for each floor, a control device in each car for starting that car, a stopping means for each car, and means responsive to the position of the first car to approach the most distant registered call regardless of the direction of that registered call for operating the stopping means of that car to stop it at the floor of that registered call.

27. In an elevator system for operating a plurality of cars serving a plurality of floors, an up call registering device and a down call registering device for each floor, an energized "above" circuit and an energized "below" circuit, means responsive to the registration of one or more calls for deenergizing that portion of the "above" circuit corresponding to the floors below the registered call or calls, and for deenergizing that portion of the "below" circuit corresponding to the floors above the registered call or calls, a control device in each car for starting that car, individual stopping means for the cars, means responsive to the registered calls for operating the stopping means of the first car to approach in the corresponding direction, and means responsive to the energized portion of the said circuits for stopping the first car to approach a registered call in the opposite direction when it is the farthest registered call in the direction of operation of that car.

28. In an elevator system for operating a plurality of cars serving a plurality of floors, a control device disposed in each car for starting that car, a stopping means for each car, an up control device and a down control device at each floor common to the cars, an energized "above" circuit and an energized "below" circuit common to all the cars, means responsive to the operation of a control device at a floor for deenergizing that portion of the "above" circuit corresponding to the floors below the floor of the operated control device, and for deenergizing that portion of the "below" circuit corresponding to the floors above the floor of the operated control device, an opposite call device for each car for operating the stopping device of that car, and means responsive to the approach of the first car to the energized portion of that circuit corresponding to the direction of that car for connecting the opposite call device of that car to that energized circuit whereby the stopping of that car will be effected at the next floor in the direction of operation of that car.

PHILLIP C. KEIPER.
